[57] CLAIM

The ornamental design for an instrument case molding, substantially as shown.

DESCRIPTION

FIG. 1 is a perspective view of the molding of the present invention;

FIG. 2 is a rear elevation thereof;

FIG. 3 is a top plan view thereof;

FIG. 4 is a side elevational view;

FIG. 5 is a vertical sectional view taken on the line 5—5 shown in FIG. 2; and

FIG. 6 is a bottom plan view.

FIG. 1

FIG. 3

FIG. 2

FIG. 4

FIG. 5

FIG. 6
